FLAT SPRAY ATOMIZING NOZZLE
William F. Steinen, Short Hills, N.J., % Wm. Steinen
Mfg. Co., 43 Bruen St., Newark, N.J.
Filed July 29, 1959, Ser. No. 830,345
9 Claims. (Cl. 239—492)

The present invention relates to a flat spray atomizing nozzle and it particularly relates to a device for spraying aqueous or other liquids under high pressure for various purposes such as for the spraying of paints, irrigating liquids, fertilizers, metal treating liquid compositions and the like.

It is among the objects of the present invention to provide a high pressure atomizing nozzle which is especially advantageous in producing thin coatings of sprayed material which will produce a predetermined oval-shaped spray pattern which is particularly designed for spraying paints and other liquids, whereby it will be possible to use a relatively simple, readily produced and machined spray nozzle construction, which nozzle will be effective without the use of air or gas as an atomizing agent.

Another object is to provide a nozzle construction using hydraulic pressure for spraying without use of air or gas in which an elongated spray will be obtained without the necessity of utilizing complicated nozzle constructions and whereby by provision of a relatively simple nozzle head, an elongated spray pattern will be obtained.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects it has been found most satisfactory according to the preferred embodiment of the present invention to provide a main body for the nozzle having a centrally drilled passage through the spray tip thereof which opens upon an elongated peaked or ridged element at the central maximum elevation thereof.

Desirably the spray opening starts from a relatively wide internal chamber and is relatively narrow at its commencement and then slightly wider along a curvature extending along the top of the peaked ridge.

The spray angle is controlled by the radius of the enlargement which widens the bore and there is provided a disc or other insert which permits the water or other liquid to flow in a spiral or whirling motion toward the opening.

This insert has slots which are used to control the quantity of liquid which flows into the opening and there will be a sufficiently wide and deep swirl chamber to assure that the liquid will pass through the opening in the nozzle at a relatively high circumferential velocity.

In the preferred form of the invention it is desired that the central peak have grooves along each side thereof with relatively elongated flat parallel plateaus on each side of the main groove.

In an alternative form of the invention there is a single peak with a central opening therein with the sides falling sharply down to the lower part of the nozzle device and without any parallel ridges or plateaus.

In either case there will be a fine elongated flat spray particularly useful for painting, irrigating, and many other

2

industrial purposes, the pattern of which may be deliberately controlled according to the exact type of spray it is desired to achieve. This will be accomplished without the use of air or gas as an atomizing agent.

5 With the foregoing and other objects in view, the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereinafter appended.

In the drawings wherein like reference characters denote corresponding parts throughout the several views:

15 FIGURE 1 is a side elevational view of one form of nozzle according to the present invention.

FIGURE 2 is a top plan view upon an enlarged scale as compared to FIG. 1, showing the central ridge or opening therein and the parallel adjacent valleys and elongated plateaus.

20 FIGURE 3 is a transverse sectional view upon the line 3—3 of FIG. 2.

FIGURE 4 is a transverse sectional view upon the line 4—4 of FIGS. 2 and 3.

25 FIG. 5 is a transverse top plan view of the insert of FIG. 8 with the outer body omitted.

FIG. 6 is a side elevational view of an alternative construction showing a single elongated peak or ridge.

FIGURE 7 is a top view on the line 7—7 of FIG. 6.

30 FIGURE 8 is a side sectional view upon line 8—8 of FIG. 7.

FIGURE 9 is a fragmentary top sectional view at right angles to FIG. 8.

Referring to the first embodiment, namely FIGS. 1—4, 35 there is shown a nozzle body A having an insert B in the central chamber C. At the top of the nozzle there is provided a central elongated ridge D which receives the spray opening E which has parallel valleys F and elongated side plateaus of semi- or sharply-circular shape as indicated at G. The insert B has a lower threaded portion which is screwed into a threaded portion of the nozzle body and has the flattened sides shown in face view in FIGS. 3 and 8 and side view in FIG. 4 and top view in FIG. 5 to permit liquid to flow past the thread and into the chamber between the insert B and the nozzle body A.

The main body A has a reduced diameter extension 10 with a lower threaded mounting portion 11. Above this threaded portion is a step 12.

Above the step 12 is a hexagon portion 13 which terminates in the dome portion 14. The dome portion 14 has a top relatively flat mount 15 of circular shape which is closed by the ridge D; the grooves F and the plateaus G.

55 In the middle of the ridge and restricted to the high portion of the ridge is the opening E. This opening E is formed by drilling through at the peak 16 the cylindrical passageway 17. This entrance 16 is at the convergence or at the top of the conical wall 18 which terminates the cylindrical wall 19 of the chamber C.

More than half way up the length or height of the passageway 17 it is caused to flare outwardly as indicated at 24 in the direction of the length of the ridge D with a slighter flare being provided at 25 transverse to the 60 ridge D.

This gives the oval form of opening 20 indicated in FIG. 2.

Internally of the chamber C there will be a disk 21 which may be threaded into position for the tangential or oblique slots 22 in the beveled face 23 thereof which fits closely across the oblique conical fact 18.

The threaded portion of the disk 21 is flattened as shown in FIGS. 3, 4, 5 and 8 to permit liquid to flow into the chamber between the insert and the body. It will be noted that the top of the insert has a central peak shown in side sectional view in FIG. 3 and top view in FIG. 5 and in side view in FIGS. 4 and 8 to guide the liquid from the grooves 22 into the conical chamber forming an entrance to the bore 16.

An important feature of the present invention is the fact that the bore 16 opens on a flat face on the top of a ridge D or 51 and that it is flared outwardly so as to form a gore-shaped opening in this flat face from side to side but only a short distance as compared to the length of the ridge which extends the full width of the top of the dome 14 of FIGS. 1 to 4 and the corresponding dome of FIGS. 6 and 7 with the flat faces 50 extending obliquely upwardly to the ridge 51.

The top 35 of the disc 21 will leave a space 36 leading to the inlet 16 of the passageway 17 which forms a swirl chamber 36.

This swirl chamber 36 will assure that the liquid flowing into the bore 17 will have a whirling movement.

As the whirling liquid leaves the widened portions 24 and 25 and the oval outlet in the peak or ridge D it forms an elongated flat spray which has a very definite outline the dimensions of which can be readily controlled by the curvature indicated at 24 and 25. The less curvature the more narrow the spray and the more curvature the wider the spray. The deeper the curvature extends into the bore 17 normally the wider the spray which will be produced.

This type of orifice with the peaked ridge and the side stabilizing grooves F and plateau formations G will give a most stable spray outline and oval-shaped spray pattern where accuracy is required as in spraying paints.

The radius of the curvature 24 and 25 will most accurately control the pattern. The swirling of the liquid will cause it to accurately follow the curvature 24-25.

In the alternative form of invention showing a ridge without the side valleys as indicated in FIGS. 5 and 6, there will be two large flats 50 on each side of the spray nozzle forming inclined sides with a single ridge 51 at the top therein.

This ridge will have a central opening 52 having an inlet at 53 from the conical chamber 54 and it will have a slight lateral curvature at 55 and a relatively wider curvature at 56 leading to the opening in the peak of the ridge.

These curvatures 55 and 56 will control the spray pattern and again will give a relatively wide elongated spray even though only a minute opening is provided in the center of the ridge 51.

The construction of the nozzle of FIGS. 5 and 6 is otherwise the same as the construction of the nozzle of FIGS. 1 to 4.

The applicant has thus provided a novel stabilized spray pattern which may be widely utilized in spraying paints and for other industrial purposes, which may be precisely determined in shape and form by the curvature of the outlet of the axial minute opening leading into the ridge which in the preferred form has parallel stabilizing valleys and parallel plateau portions on each side of said valleys.

While there has been herein described a preferred form of the invention, it should be understood that the same may be altered in details and in relative arrangement of parts within the scope of the appended claims.

Having now particularly described and ascertained the nature of the invention, and in what manner the same is to be performed:

What is claimed is:

1. A flat spray circular-dome top-bottom screw mount nozzle having a top dome head with an outer spherical surface and an intermediate hexagon base and a terminal depending reduced diameter threaded mounting element, said head having an upper transversely extending flat top narrow ridge with sharply descending oblique side faces on each side of said ridge formed integrally with upper part of the top head and projecting above the spherical surface, said head and said base and said terminal having a central wide diameter threaded axial circular first passageway therethrough terminating in a conical end portion directly below the top of the dome and a cylindrical axial small diameter second passageway leading from the conical end portion to and opening in the central part of the ridge with the opening extending substantially to and into said oblique sides.
2. The nozzle of claim 1, the end of the second passageway at the flat ridge flowing longitudinally and laterally and a plug threaded into said first passageway forming an annular flow chamber within the adjacent portions of the base and the lower part of the head and said plug having a conical end portion with oblique slotted passageways therein abutting the end of the first passageway.
3. A flat spray atomizing nozzle for spraying paint and liquids in oval shaped spray patterns hydraulically without air and gas as an atomizing agent comprising an interiorly recessed cup shaped body having an exterior dome shaped upper transversely ridged spray end, an exterior enlarged intermediate hexagon portion and an exterior small diameter threaded inlet end, a transverse flat face transversely extending ridge at the top of the dome, the interior of the body having a conical end recess at the end of the interior recess and an enlarged chamber next to the conical end recess and a threaded portion extending from said chamber to the inlet end of the fitting; and an insert having a threaded inlet end threaded into said threaded portion, a cylindrical portion inside of said enlarged chamber leaving a peripheral annular chamber and a conical head portion abutting said conical end recess, said head portion having flow passageways on the abutting faces thereof, there being a small conical chamber formed between the end of the conical end recess and the conical head portion and an axial flow bore passageway in said dome opening into said flat face of the ridge at its outlet end and into said small chamber at its inlet end.
4. The nozzle of claim 3, said conical head portion being flattened at its end transversely to the axis of the nozzle and said flattened portion having a conical projection extending toward and substantially to the inlet axial flow passageway.
5. The nozzle of claim 3, threaded inlet end having diametrically opposite flattened faces to permit liquid to flow into said annular chamber and said insert being stepped down in diameter on each side of said cylindrical portion to increase the width of said peripheral chamber adjacent the ends of said chamber.
6. The nozzle of claim 3, said ridge being part of a top flat plateau on said dome and said ridge being formed by transversely grooving said plateau on each side of the opening of said axial flow bore passageway.
7. The nozzle of claim 3, said outlet end of said bore passageway being flared outwardly so as to form a gore shaped opening on said flat face of the ridge having a width substantially equal to the width of the ridge and having a length substantially short of the length of the ridge.
8. The nozzle of claim 3, said dome being obliquely flattened on each side of said ridge so that the sides of the nozzle will abruptly fall away from the periphery of the ridge.
9. The nozzle of claim 3, said conical head portion having a right angular recess at the base of the conical head and having a peripheral recess at the top of the

head portion and said flow passageways consisting of right cross section recesses extending obliquely across top face of the conical head portion so as not to intersect the inside opening of said axial passageway.
